REVISED SPIN DRAFTER

Olle E. Sandelin, Cleveland, Ohio, assignor to The Warner & Swasey Company, Cleveland, Ohio, a corporation of Ohio

Application April 30, 1952, Serial No. 285,185

6 Claims. (Cl. 19—131)

This invention relates to improvements in drafting fiber strands such as tops, slivers, rovings, slubbings, and the like, in bundles or aggregates, all of which are referred to for convenience as fiber strands or slivers. The invention is particularly concerned with features rendering it practical to draft crimped staple fibers by drafting heads of the type having spaced pairs of rollers nipping the fiber strand at the exit and entrance ends of the drafting ratch and having a higher speed at the exit end than at the entrance end of the ratch.

An object of the invention is to draft crimped fibers uniformly and without causing bunching or flow of the fibers in the strand.

Another object of the invention is to improve the fiber control during drafting in drafting heads of the type mentioned with one or more air streams.

A more specific object of the invention is to improve the control of crimped synthetic fibers during drafting in drafting heads of the type mentioned by sucking fibers of the strand towards a moving member along at least part of the drafting ratch so that the fibers are held approximately stationary in relation to the moving member until they are gripped by the drafting rollers at the exit end of the drafting ratch.

A further object is to provide a drafting head in which the moving member has the form of a moving endless belt which is pervious to air.

Still another object is to provide a drafting head in which the action of the moving endless air-pervious belt is supplemented by second moving endless belt which is highly flexible and impervious to air and lies against the opposite side of the strand from the air-pervious belt.

An additional object of the invention is to provide a nipping action for the fibers of fiber strand intermediate the entrance and the exit ends of a drafting ratch and at a distance from the exit end which is somewhat greater than the average length of the longest fibers in the strand.

Another additional object of the invention is to provide a soft nipping action for the fibers of a strand which is being held between a moving air pervious belt and a flexible impervious belt at a location close to the exit end of a drafting ratch to stretch the slow moving crimped fibers and to remove the crimp in the fibers.

Other and further objects, features and advantages of the invention will become apparent from the following description considered in conjunction with the accompanying drawings, in which

Fig. 1 is an elevation in diagrammatical form, partly in section, of a drafting head embodying the invention.

Fig. 2 is a fragmentary view of a belt to be used in the construction of Fig. 1.

Fig. 3 is a cross-sectional view of a multiple trumpet guide employed in the apparatus of Fig. 1 and represented as a section cut by a plane 3—3 indicated in Fig. 1.

Fig. 4 is a view in perspective of the suction box employed in the embodiment of Fig. 1.

Fig. 5 is a fragmentary cross-sectional view of the suc-

2

tion box of Fig. 4 represented as cut by a plane 5—5 indicated in Fig. 1.

Fig. 6 is a fragmentary cross-sectional view of a portion of the apparatus of Fig. 1 represented as cut by a plane 6—6.

Like reference characters are utilized throughout the drawing to designate like parts.

Referring particularly to Fig. 1 the drafting head comprises a pair of ratch rolls 11—12 mounted adjacent a multiple trumpet guide 13 for receiving a plurality of slivers or strands 14 of crimped synthetic fibers, a pair of drafting rolls 15—16 mounted at the end of the drafting ratch and an air pervious surface member in the form of a belt or apron 17 arranged to have a portion of the surface 18 thereof continuously traveling in the drafting ratch. For applying suction to the air-pervious apron 17 a suction box 19 is provided having a top wall 21 along which the belt 17 is adapted to travel.

Preferably, as shown, the ratch rolls 11 and 12 are of different size, the upper roll 11 having somewhat more than twice the diameter of the lower roll 12 and the roller 12 serves also as a guide roll for the air-pervious apron 17. The draft rolls 15—16 are also preferably of unequal size and of different size from the ratch rolls 11—12. The upper drafting roll 15, as shown, is of nearly twice the diameter of the lower draft roll 16 and larger in diameter than the upper ratch roll 11. The lower drafting roll 16 is smaller than the upper ratch roll 11 and approximately twice the diameter of the lower ratch roll 12.

A drive roll 22 is provided for the apron or belt 17 and suitable guide rolls 23 are also provided. The forward edge 29 of the top wall 21 of the suction box 19 is rounded as shown to form a forward guide for the belt 17.

As shown in Fig. 2 the belt 17 is provided with air-pervious zones 24, each of which corresponds to one of the fiber strands 14, and the remainder of the belt 17 is preferably impervious to air. The air-pervious zone 24 as shown in Fig. 2 may take the form of staggered rows of holes 25.

The suction box 19 has its top wall 21 perforated to permit applying suction through the openings 25 in the belt 17 and has an exhaust connection 27 adapted to be connected through a suction pipe to an exhaust fan or vacuum pump, not shown. Preferably the upper wall 21 of the suction box 19 also has its perforations arranged in air-pervious zones 28 corresponding to the air pervious zones 24 in the belt 17.

It has been found that crimped artificial or synthetic staple fibers present a greater problem in drafting than natural fibers, whether of animal or vegetable source, for the reason that the surfaces of such fibers normally provide relatively little adhesion or frictional effect and are relatively slippery. The adhesion of such fibers to each other and to the apron 17 is promoted by the suction provided by the suction box 19. In order to obtain the maximum degree of uniformity of the fiber strands, I prefer to provide additional fiber control at a spacing

somewhat greater than the average length of the longest fibers in the strand. To this end a crimped fiber-holding apron-nip roll or pressure roll 31 is provided in the drafting ratch having reduced bearing portions or shafts 30 resting in bearing blocks 32, adjustably mounted by means of longitudinal slots 33 in side plates 34 secured to the top wall 21 of the suction box 19. It is to be understood that the bearing blocks 32 are movable in one direction or another in the slots 33 and then secured by suitable means such as bolts or screws 35 so that the distance between the axis of the roll 31 and the line of centers of draft rolls 15—16 will exceed the average length of the longest fibers in the strand. The end portions of the air-per-

vious zones 28 in the top wall 21 of the suction box 19 may take the form of slots 36. The central portions of the air-pervious zones 28 in the suction box 19, however, are preferably in the form of rows of holes 37 in order to minimize the sagging effect of the belt 17 and the sliver 14 held thereto by suction. The holes 37 are preferably elongated or elliptical with oblique axes so as to form obliquely transverse slots or apertures.

In order to increase the effectiveness of the suction an upper surface member in the form of an endless belt or apron 38 is preferably also provided which travels along the drafting ratch, contacting the air permeable surface 18 and the strands 14 and passing around the crimped fiber holding roller 31 and the ratch roll 11. For guiding the front end of the belt 38 a cross strip or bar 39 is provided, which has a relatively narrow rounded nose 41 nipping into the space bounded by the surfaces of the draft rolls 15—16 and an imaginary plane tangent thereto. Preferably the apron guide 39 is pivoted at the rear end on a cross-rod 42 and the nose 41 is resiliently pressed downward by a suitable means such as an adjustable torsion spring 43. The apron 38 is composed of relatively light flexible material which is impervious to air such as rubber-impregnated fabric.

Preferably the crimped fiber control or holding roller 31 is loaded, such as by weights hung from the ends of the bearing portions or shafts 30, and the bearings 44 are elongated vertically. Loading may be applied by means of bearing caps 45 adapted to be pressed downwardly by screws 46 but preferably the caps 45 also have vertically elongated journal cavities in order to form a journal box which holds the journals captive but permits vertical movement. In this manner, bunched fibers are permitted to pass without change in pressure in apron nip or jamming. Although the invention is not limited to specific values of pressure, it has been found that satisfactory results may be obtained by loading the control roller 31 to give a pressure of approximately 50 pounds on the four strands 14 while the strength of the torsion spring 43 is adjusted to give a loading of about 2 pounds to the nose 41 of the apron guide 39. A relatively soft fiber control or faint nip is provided at the exit end of the ratch with a pressure control in the center portion of the ratch, just beyond the end of the longest fibers nipped by the draft rolls 15—16.

The nose portion 41 of the guide bar 39 gives "soft" control of the fibers of the four strands 14 at a location close to the nip of the draft rolls 15—16 to permit fast moving fibers of the strands to slip through such a "faint" nip while slow moving fibers are not influenced by the movement of the fast running fibers.

As illustrated in Fig. 5 the suction in the suction box tends to suck the strands 14 against the air pervious apron 17 and causes some sagging thereof in the longitudinal slots 36 while the apron 38 is drawn downward against the strands 14. On the sides, as at 47, air tends to rush inwards between the two surface members at their edges, causing the outer edge 47 of the upper belt 38 to lie against the lower belt 17. Thus the slivers 14 are compressed into elliptical form.

At the part of the suction box 19 at which the crimped fiber holding roller 31 rests, additional pressure is applied to the strand 14 by the loading of the roller 31. Sagging of the lower belt 17 is then minimized by the fact that the air pervious zone in the top wall 21 of the suction box 19 consists only of relatively narrow oblique perforations 37. The pressure roll 31, in its various adjusted positions, will have line pressure contact with the upper surface of the suction box 19 at the central portion thereof and bridges the rows of oblique holes therein.

The control of the strands in the drafting zone is carried out by the suction of air which draws the thin flexible top apron 38 towards the surface of the pervious bottom apron thus producing a frictional resistance to the move-

ment of the fibers of the four strands 14 passing between said aprons, and also producing a restraining action to prevent the fibers of the strands from spreading during drafting.

5 Additional control of the fiber strands in the drafting zone is carried out by the action of the pressure roller on the strands at a location intermediate the entrance and the exit ends of the drafting ratch and also by the soft nipping action on the strands by the nose at a location in 10 close proximity to the exit end of the drafting ratch.

While the invention has been described as embodied in concrete form and as operating in a specific manner in accordance with the statutes it should be understood that the invention is not limited thereto, as various modifications will suggest themselves to those skilled in the art without departing from the spirit of the invention.

What is claimed is:

1. In a crimped-fiber-strand drafting head of the type having a pair of draft rolls nipping the strand at the exit 20 end of the drafting ratch, a member having a surface moving in a pathway along and within the drafting ratch in a direction from the entrance and toward the exit end, and continuously contacting the strand along at least a part of the drafting ratch, said member being formed

25 with a row of staggered holes therein to render it air pervious therewith, a roller mounted in the ratch for holding crimped fibers within the strand, a suction device comprising a box having a wall with an air pervious zone therein corresponding with the air pervious zone of the 30 air pervious surface member, said air pervious zone comprising slots at either end thereof and a row of perforations between said slots in the portion of said wall under said crimped fiber holding roller, said box having an outlet to be connected to a vacuum line.

3. In a crimped-fiber-strand drafting head of the type having a pair of draft rolls nipping the strand at the exit end of the drafting ratch, a member having a surface moving in a pathway along and within the drafting ratch in a direction from the entrance and toward the exit end,

40 and continuously contacting the strand along at least a part of the drafting ratch, said member being formed with a row of staggered holes therein to render it air pervious therewith, a roller mounted in the ratch for holding the crimped fibers within the strand, a suction device comprising a box having a wall with an air pervious zone therein corresponding with the air pervious zone of the 45 air pervious surface member, said air pervious zone comprising slots at either end thereof and a row of perforations between said slots in the portion of said wall under said crimped fiber holding roller, said box having an outlet to be connected to a vacuum line, a second member in the form of a belt having a surface also moving in a pathway along and within the drafting ratch, continually contacting the fiber strand on the side opposite the first

50 such member, the second mentioned surface member being relatively thin and flexible whereby an enclosure of substantially elliptical cross-section is formed for confining the fiber strand, said crimped fiber holding roller mounted in the ratch and bearing upon the second mentioned surface member for holding the crimped fibers within the strand.

5. In a crimped-fiber-strand drafting head of the type having a pair of draft rolls nipping the strand at the exit end of the drafting ratch, a member having a surface moving in a pathway along and within the drafting ratch in a direction from the entrance and toward the exit end, and continuously contacting the strand along at least a part of the drafting ratch, said member being formed with a row of staggered holes therein to render it air pervious therewith, a roller mounted in the ratch for holding the crimped fibers within the strand, a suction device comprising a box having a wall with an air pervious zone therein corresponding with the air pervious zone of the air pervious surface member, said air pervious zone comprising slots at either end thereof and a row of perfora-

tions between said slots in the portion of said wall under said crimped fiber holding roller, said box having an outlet to be connected to a vacuum line, a second member in the form of a belt having a surface also moving in a pathway along and within the drafting ratch, continually contacting the fiber strand on the side opposite the first such member, the second mentioned surface member being relatively thin and flexible whereby an enclosure of substantially elliptical cross-section is formed for confining the fiber strand, a guide member extending transversely at the front end of the ratch with a guiding nose lying within the space bounded by the cylindrical surfaces of the said draft rolls and the plane tangent thereto for guiding the second surface member and the strand well into the nip of said draft rolls, said crimped fiber holding roller mounted in the ratch and bearing upon the second surface member for holding the crimped fibers within the strand.

4. In a crimped-fiber-strand drafting head of the type having a pair of draft rolls nipping the strand at the exit end of the drafting ratch, a member having a surface moving in a pathway along and within the drafting ratch in a direction from the entrance and toward the exit end, and continuously contacting the strand along at least a part of the drafting ratch, said member being formed with a row of staggered holes therein to render it air pervious therealong, a roller mounted in the ratch for holding the crimped fibers within the strand, a suction device comprising a box having a wall with an air pervious zone therein corresponding with the air pervious zone of the air pervious surface member, said air pervious zone comprising slots at either end thereof and a row of perforations between said slots in the portion of said wall under said crimped fiber holding roller, said box having an outlet to be connected to a vacuum line, a second member in the form of a belt having a surface also moving in a pathway along and within the drafting ratch, continually contacting the fiber strand on the side opposite the first such member, the second mentioned surface member being relatively thin and flexible whereby an enclosure of substantially elliptical cross-section is formed for confining the fiber strand, a guide member extending transversely at the front end of the ratch with a guiding nose lying within the space bounded by the cylindrical surfaces of the said draft rolls and the plane tangent thereto for guiding the second surface member and the strand well into the nip of said draft rolls, the said front guide member having the rear end thereof secured to a spring for resiliently holding the nose of the guide member downward and providing soft control of the crimped fiber relatively close to the nip of the drafting rolls, said crimped fiber holding roller mounted in the ratch and bearing upon the second surface member for holding the crimped fibers within the strand.

5. In a crimped-fiber-strand drafting head of the type having a pair of draft rolls nipping the strand at the exit end of the drafting ratch, a member having a surface moving in a pathway along and within the drafting ratch in a direction from the entrance and toward the exit end, and continuously contacting the strand along at least a part of the drafting ratch, said member being formed with a row of staggered holes therein to render it air pervious therealong, a roller mounted in the ratch for holding the crimped fibers within the strand, a suction device comprising a box having a wall with an air pervious zone therein corresponding with the air pervious zone of the air pervious surface member, said air pervious zone comprising slots at either end thereof and a row of perforations between said slots in the portion of said wall under said crimped fiber holding roller, said box having an outlet to be connected to a vacuum line, a second member in the form of a belt having a surface also moving in a pathway along and within the drafting ratch, continually contacting the fiber strand on the side opposite the first such

- member, the second mentioned surface member being relatively thin and flexible whereby an enclosure of substantially elliptical cross-section is formed for confining the fiber strand, a guide member extending transversely at the front end of the ratch with a guiding nose lying within the space bounded by the cylindrical surfaces of the said draft rolls and the plane tangent thereto for guiding the second surface member and the strand well into the nip of said draft rolls, the said front guide member having the rear end thereof secured to a spring for resiliently holding the nose of the guide member downward and providing soft control of the crimped fiber relatively close to the nip of the drafting rolls, said crimped fiber holding roller mounted in the ratch and bearing upon the second surface member for holding the crimped fibers within the strand, and means for holding the crimped fiber holding roller with a pressure substantially greater than that of the guiding member for the second surface member.
- 20 6. In a crimped-fiber-strand drafting head of the type having a pair of draft rolls nipping the strand at the exit end of the drafting ratch, a member having a surface moving in a pathway along and within the drafting ratch in a direction from the entrance and toward the exit end, and continuously contacting the strand along at least a part of the drafting ratch, said member being formed with a row of staggered holes therein to render it air pervious therealong, a roller mounted in the ratch for holding the crimped fibers within the strand, a suction device comprising a box having a wall with an air pervious zone therein corresponding with the air pervious zone of the air pervious surface member, said air pervious zone comprising slots at either end thereof and a row of perforations between said slots in the portion of said wall under said crimped fiber holding roller, said box having an outlet to be connected to a vacuum line, a second member in the form of a belt having a surface also moving in a pathway along and within the drafting ratch, continually contacting the fiber strand on the side opposite the first such member, the second mentioned surface member being relatively thin and flexible whereby an enclosure of substantially elliptical cross-section is formed for confining the fiber strand, a guide member extending transversely at the front end of the ratch with a guiding nose lying within the space bounded by the cylindrical surfaces of the said draft rolls and the plane tangent thereto for guiding the second surface member and the strand well into the nip of said draft rolls, the said front guide member having the rear end thereof secured to a spring for resiliently holding the nose of the guide member downward and providing soft control of the crimped fiber relatively close to the nip of the drafting rolls, said crimped fiber holding roller mounted in the ratch and bearing upon the second surface member for holding the crimped fibers within the strand, means for holding the said crimped fiber holding roller with a pressure substantially greater than that of the guiding member for a second surface member, and slotted members on either side of the perforated wall of the suction box for adjustably supporting the crimped fiber holding roller to enable it to be spaced from the nip of the draft rolls a distance as great as the average length of the longest fiber of the strand of crimped fibers.
